(57) **CLAIM**

We claim the ornamental design of a manifold adaptor for a multi-barrel syringe applicator, as shown and described.

DESCRIPTION

FIG. 1 is a front perspective view of a manifold adaptor for a multi-barrel syringe applicator;

FIG. 2 is a rear perspective view of a manifold adaptor for a multi-barrel syringe applicator;

FIG. 3 is a front elevational view of a manifold adaptor for a multi-barrel syringe applicator;

FIG. 4 is a rear elevational view of a manifold adaptor for a multi-barrel syringe applicator;

FIG. 5 is a left-side elevational view of a manifold adaptor for a multi-barrel syringe applicator, which is identical to the right-side elevational view; and,

FIG. 6 is a top plan view of a manifold adaptor for a multi-barrel syringe applicator, which is identical to the bottom plan view.

The broken lines showing parts of the drawings is included for the purpose of illustration use and environment and forms no part of the claimed design.
